(57) **CLAIM**

The ornamental design for an access cover key for swimming pool water recirculation system, as shown and described.

DESCRIPTION

FIG. 1 is a front perspective view of an access cover key for swimming pool water recirculation system;
FIG. 2 is a front elevational view thereof;
FIG. 3 is a right side elevational view thereof;
FIG. 4 is a left side elevational view thereof;
FIG. 5 is a rear elevational view thereof;
FIG. 6 is a bottom plan view thereof;
FIG. 7 is a top plan view thereof; and,
FIG. 8 is a rear perspective view thereof.

The broken lines in the drawings depict portions of the access cover key for swimming pool water recirculation system that form no part of the claimed design.
